UNITED STATES PATENT OFFICE.

WILLIAM H. LONG, OF BERKELEY, CALIFORNIA.

COMBINATION-LOCK.

1,364,445.

Specification of Letters Patent.

Patented Jan. 4, 1921.

Application filed June 12, 1920. Serial No. 388,443.

To all whom it may concern:

Be it known that I, WILLIAM H. LONG, a citizen of the United States, and a resident of Berkeley, county of Alameda, and State 5 of California, have invented a new and useful Combination-Lock, of which the following is a specification.

My invention relates to combination locks and particularly to a lock of this type which 10 may be used to lock certain of the vital parts of an automobile to prevent the theft thereof.

An object of the invention is to provide a combination lock in which the tumblers 15 are operable entirely independent of the central shaft or spindle.

Another object of the invention is to provide a combination lock in which the dial member is rotatable independent of the central 20 shaft.

A further object of the invention is to provide a lock of the present type which may be adjusted so finely that the least departure from the use of the exact combination 25 will prevent the opening of the lock.

A further object is to provide a combination lock which will readily lend itself to locking some of the vital parts of an automobile, especially such parts as are usually 30 difficult to lock against movement on account of their mechanical nature.

The invention possesses other objects and features of advantage, some of which, with the foregoing, will be set forth in the following 35 description of the preferred form of my invention which is illustrated in the drawings accompanying and forming part of the specification. It is to be understood that I do not limit myself to the showing made by the said drawings and description, as I may adopt variations of the preferred 40 form within the scope of my invention as set forth in the claims.

Referring to said drawings:

45 Figure 1 is a front elevation of one form of the lock.

Fig. 2 is a vertical longitudinal section thereof.

Fig. 3 is a rear elevation of the lock.

50 Fig. 4 is a front view of the bearing member and the tumbler rings.

Fig. 5 is a vertical longitudinal section of the bearing member.

Fig. 6 is a perspective view of one of the 55 tumbler rings.

Fig. 7 is a perspective view of the dial member.

Briefly expressed the lock in its present embodiment comprises a casing through which extends the main spindle that is 60 adapted to retain one or more extraneous elements in locked position. Arranged within the casing and adapted to hold the spindle in its locking position is a bolt which is engaged by a number of tumbler 65 rings having notches which, when alined, permit the bolt to be disengaged from the spindle so that the extraneous member may be released. A manually operative dial member rotatably disposed about the spindle affords a means of manipulating the tumblers so that they may be positioned to permit or prevent the release of the bolt 70 as the case may be. Means are provided for resiliently retaining the bolt in engagement with the spindle and means are also included for ejecting the bolt from such engagement.

A detailed description of my invention follows:

As hereinbefore mentioned my lock is particularly adapted for locking various parts of an automobile; in this connection I have in the present embodiment of the invention incorporated it with the ignition and light- 85 ing switch which is usually provided on the dash of the automobile. I here merely provide for the locking of the ignition, the lights being controlled by a lever, which may be readily moved at any time.

The device preferably comprises a cylindrical casing 2 formed with an annular flange 3 which enables the lock to be properly fitted on dash 4 of the automobile. The rear portion of the casing, which, of course, 90 lies behind the dash, is provided with a switch board 6 preferably formed of some di-electric material upon which the ignition terminal posts 7 and the lighting terminal posts 8 are arcuately arranged. The posts 100 8 are adapted to be engaged by a contact 9 secured to a di-electric disk 11 which is rotatably mounted within the casing. The disk is rotated by means of a lever or handle 12 which extends through a transversely disposed slot 13 formed in the casing prefer-

ably just in front of the exposed surface of the flange 3. Manipulation of the lever 12 will produce a corresponding movement of the contact 9 whereby the lights may be 5 turned off, on, or dimmed as desired.

The ignition terminal posts 7 are arranged to be engaged by a contact 14 which is fixed upon a second di-electric rotatable disk 16 whose movement, to effect the opening or closing of the ignition circuit, is controlled through the agency of my lock in the manner which will now be described.

Arranged within the casing and suitably held against movement therein is a bearing member 17 in which engages and through which extends the main locking spindle 18. The disk 16, upon which is held the ignition contact 14, is fixed to the spindle by means of a pin 19, a suitable slot 21 being formed in the bearing to permit the proper co-movement of the spindle and disk. Movement of the pin 19, and therefore the disk 16, is limited in opposite directions by the end walls 22 and 23 of the slot, the contact 14 being arranged to close the circuit when the pin engages one end 23 of the slot, and to open the circuit when the other end 22 of the slot is engaged.

It is therefore primarily desirable to lock 30 the spindle when the pin 19 thereof engages the end 22 of the slot so that it will be impossible to start the automobile with its own motive power. Extending radially of the spindle and slidably in the bearing member 17 is a bolt 26 whose inner end is arranged to seat in a recess 27 formed in the spindle. The recess is formed with a cam face 27a, as clearly shown in Fig. 3, so that the bolt must be ejected from recess before 35 the spindle can be rotated.

Means are therefore provided for holding the bolt engaged in the recess so that the rotation of spindle will be prevented. Mounted for independent rotation in the bearing 40 member 17 and concentrically disposed about the spindle are a plurality of tumbler rings 28, 29 and 30 which engage recesses 31, 32 and 33, respectively formed in the bolt, thereby retaining the bolt in engagement 45 with the spindle. Each tumbler ring is formed with a notch 34 which is substantially of the shape of that portion of the bolt which the ring engages, therefore, it will be apparent that when the notches 34 50 are radially alined at the bolt that the latter may pass through the rings and thus permit the spindle to be rotated. Means are included whereby the tumblers may be manipulated so as to move the notches 34 into or out of 55 alinement with the bolt according as it may be desired by the proper person to lock or release the spindle. Rotatably mounted on the spindle and covering the front of the lock is a manually operative dial member 36 60 having the usual index numerals formed

thereon. The inner face of the dial member is formed with projections 37, 38 and 39 which are arranged to engage projections 40, 41 and 42 respectively fixed on the tumblers. As shown clearly in Fig. 4 the two 70 inner tumblers are provided with a pair of projections 40 and 41 respectively whereas the outer tumbler is preferably provided with but one projection 42.

To operate the lock, assuming that it is desired to release the spindle so that the ignition circuit may be closed, the dial member is rotated in the usual manner, first in one direction, then in the opposite direction, and so on, until the tumbler notches are 80 alined at the bolt, the amount of rotation of the tumblers in each direction being, of course, governed by the particular spacing of the projections 40, 41 and 42 in the respective tumblers. With the notches thus 85 alined the spindle may be rotated by the handle 47 fixed thereto so as to move the contact to close the circuit, the bolt being in the meantime ejected from the recess against the resistance only of the spring 48 and 90 moved through the tumbler notches.

To now move the contact back to open the circuit and lock it in said position, the spindle is rotated to move the contact out of engagement with the posts, during which 95 movement the bolt has been pressed into the spindle recess by the spring 48. The dial member may then be rotated one or more turns to move the notches out of alinement with the bolt so that the latter is held in 100 locked engagement with the spindle.

It will be noted that the tumbler rings are each provided with quite a number of circumferentially alined apertures 49 whereby the projections or pegs 40, 41 and 42 may be 105 placed in a different aperture whenever it is desired to change the combination of the lock.

I claim:

1. A combination lock comprising a casting having a bearing, a locking spindle mounted in said bearing and extending through the casing, a tumbler ring mounted for rotation in said bearing and movable entirely independent of said spindle, said 110 tumbler having an opening, a manually operative dial member mounted for rotation on said spindle, a bolt adapted to engage said spindle and having a recess for the reception of said tumbler, co-operating projections on said tumbler and dial member 115 whereby said opening may be moved into or out of alinement with the bolt to permit the latter to be disengaged from or engaged with the spindle, means for resiliently retaining said bolt in engagement with said spindle, and means on said spindle for moving said bolt out of resilient engagement therewith.

2. A combination lock comprising a cas- 120

ing having a bearing, a locking spindle rotatably mounted in said bearing and extending through said casing, a plurality of concentrically disposed transversely alined notched tumbler rings arranged in said bearing about said spindle and rotatable independent of the latter, a manually operative dial member mounted for independent rotation on said spindle, a bolt adapted to engage said spindle and having a plurality of recesses for the reception of said tumbler rings, coöperating projections on said rings and said dial member whereby said notches may be moved into or out of alinement with said bolt to permit the latter to be disengaged from or engaged with the spindle.

3. A combination lock comprising a casing, a locking spindle extending through said casing, a plurality of concentric diametrically alined notched tumbler rings rotatably mounted about said spindle, a manually operative dial member mounted for independent rotation on said spindle, a bolt adapted to engage said spindle and provided with a plurality of recesses for the reception of said tumbler rings, and coöperative engaging means on said dial and tumblers whereby said notches may be moved into or out of alinement with said bolt to permit the latter to be disengaged from or engaged with the spindle.

4. A combination lock comprising a casing having a bearing, a locking spindle rotatably mounted in said bearing and extending through said casing, a tumbler ring

mounted for rotation in said bearing and movable independent of said spindle, said tumbler having an opening, a manually operative dial member mounted for rotation on said spindle, a bolt adapted to engage said spindle and having a recess for the reception of said tumbler, and coöperative engaging means on said tumbler and dial member whereby said opening may be moved into or out of alinement with the bolt to permit the latter to be disengaged from or engaged with the spindle.

5. A combination lock comprising a casing having a bearing, a locking spindle rotatably mounted in said bearing and extending through said casing, a tumbler ring mounted for rotation in said bearing and movable independent of said spindle, said tumbler having an opening, a manually operative dial member mounted for rotation on said spindle, a bolt adapted to engage said spindle and having a recess for the reception of said tumbler, coöperative engaging means on said tumbler and dial member whereby said opening may be moved into or out of alinement with the bolt to permit the latter to be disengaged from or engaged with the spindle, means for resiliently retaining said bolt in engagement with said spindle, and means on said spindle for moving said bolt out of resilient engagement therewith.

In testimony whereof, I have hereunto set my hand at Oakland, California, this 29th day of May, 1920.

WILLIAM H. LONG.
